(57) **CLAIM**

The ornamental design for a game piece set, as shown and described.

DESCRIPTION

FIG. 1 is a top perspective view of a game piece set;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is a top perspective view of a first piece of the game piece set shown apart for ease of illustration;
FIG. 9 is a front elevation view thereof;
FIG. 10 is a rear elevation view thereof;
FIG. 11 is a left side elevation view thereof;
FIG. 12 is a right side elevation view thereof;
FIG. 13 is a top plan view thereof;
FIG. 14 is a bottom plan view thereof;
FIG. 15 is a top perspective view of a second piece of the game piece set shown apart for ease of illustration;
FIG. 16 is a front elevation view thereof;
FIG. 17 is a rear elevation view thereof;
FIG. 18 is a left side elevation view thereof;
FIG. 19 is a right side elevation view thereof;
FIG. 20 is a top plan view thereof;
FIG. 21 is a bottom plan view thereof;
FIG. 22 is a top perspective view of a third piece of the game piece set shown apart for ease of illustration;
FIG. 23 is a front elevation view thereof;
FIG. 24 is a rear elevation view thereof;
FIG. 25 is a left side elevation view thereof;
FIG. 26 is a right side elevation view thereof;
FIG. 27 is a top plan view thereof; and,
FIG. 28 is a bottom plan view thereof.
The broken lines in the drawings depict portions of the game piece set that form no part of the claimed design.
